US00D899924S

(12) **United States Design Patent** (10) **Patent No.:** **US D899,924 S**
Stammen et al. (45) **Date of Patent:** **** Oct. 27, 2020**

(54) **PUSH BUTTON CLOSURE**

(71) Applicant: **Stolle Machinery Company, LLC**,
Centennial, CO (US)

(72) Inventors: **Dennis C. Stammen**, Brookville, OH
(US); **Patrick K. McCarty**, Dayton,
OH (US)

(73) Assignee: **Stolle Machinery Company, LLC**,
Centennial, CO (US)

(**) Term: **15 Years**

(21) Appl. No.: **29/725,016**

(22) Filed: **Feb. 21, 2020**

Related U.S. Application Data

(63) Continuation of application No. 29/699,077, filed on Jul. 23, 2019, now Pat. No. 879,608, which is a continuation of application No. 29/673,984, filed on Dec. 19, 2018, now Pat. No. Des. 857,497, which is a continuation-in-part of application No. 29/637,825, filed on Feb. 22, 2018, now Pat. No. Des. 845,764.

(57) **CLAIM**

The ornamental design for a push button closure, as shown and described.

DESCRIPTION

FIG. 1 is a top perspective view of the push button closure; FIG. 2 is another top perspective view of the push button closure;

FIG. 3 is a bottom perspective view of the push button closure;

FIG. 4 is another bottom perspective view of the push button closure;

FIG. 5 is a top plan view of the push button closure;

FIG. 6 is a bottom plan view of the push button closure;

FIG. 7 is a side elevational view of the push button closure; and,

FIG. 8 is a section view of the push button closure taken in the direction of line 8-8 shown in FIG. 5.

The broken lines shown represent unclaimed subject matter and form no part of the claimed design.
